UNITED STATES PATENT OFFICE.

ALBERT L. ZIMMERMAN, OF VALPARAISO, INDIANA, ASSIGNOR TO N. S. AMSTUTZ, OF VALPARAISO, INDIANA.

BATTERY-TERMINAL TONGS.

Application filed March 18, 1922. Serial No. 544,939.

My invention relates to improvements in battery terminal tongs and it more especially relates to the features hereinafter pointed out in the annexed claims.

5 The purpose of my invention is to provide a tool that will quickly loosen the nuts and quickly separate the connection when batteries are to be removed from automobiles etc. for recharging or repairs; that combines in 10 one tool several adaptations useful for different operations.

With these and other ends in view, I illustrate in the accompanying drawing such instances of adaptation as will disclose the 15 broad underlying features without limiting myself to the specific details shown thereon or described herein.

Fig. 1 is a side view, in perspective, showing tongs in position to remove a battery 20 terminal.

Fig. 2 is a side view of the handle portion of the tongs when it is in a closed position.

Fig. 3 is a plan view in section of the tongs showing the relation of the jaws to each 25 other.

The quick removal of the batteries from automobiles under ordinary conditions is quite impossible because the terminals, after being in service, stick so tightly that it is 30 sometimes impossible to disconnect them with ordinary means. In fact a persistence with such means, not infrequently results in broken jars or terminals, furthermore, even if the parts are finally separated without injury to the jar, there is great danger of damaging the terminal surfaces so as to cause poor connections thereafter.

These difficulties are entirely removed when my improved tongs are used. They 40 enable one to loosen the clamps which hold the battery in place on the car; to loosen the clamping nut of the battery terminal and finally make the positive removal of the terminal the matter of only a few moments.

45 The tongs comprise two handles 1 and 8 which terminate at their upper end in forked nut removing fingers 2 and 9. At the bottom end of the handles 1 and 8 they are flattened at 3 and 10 so as to lie side by side. The flattened parts 3 and 10 are enlarged at 11 and 12 to form bearings for the bolt 4 which is held in place by a nut 13.

The handle 8, beyond the enlarged part 12 is formed into a "goose neck" shape 14 that 50 curves sharply upward and then downward

into a rounded end 16. This end has a sharp point 15 which prevents its slipping off of the battery terminal 17. The other handle 1 has a right-angled toe 6 formed with an off-set 5 which clears the enlarged part 12 of the 60 handle 8. This toe ends relatively sharp into concave forward edge 7 curved to approximate the diameter of the battery terminal 17. It is made sharp to easily pass into the narrow space between the battery top and the 65 removable connecting terminal head 18 while the point 15 is in engagement with the battery terminal 17.

In this position a movement of the handles toward each other will also move the point 15 toward the toe 6, thus positively separating the two terminals 17 and 18 from each other easily and quickly after the clamping nut 21 on bolt 20 is loosened by means of the wrench end 2 to take off the tension 70 from the split projection 19 of the connecting terminal 18. The external wire is fastened to the lug 22. In replacing the battery the bent wrench end 9 is used to tighten the battery holding clamps, not shown. This 75 wrench is serrated on both of its jaws while the wrench 2 is serrated on one jaw only. The latter wrench again serves to cooperate with the nut 21 in clamping the connecting terminal 18 after it is pressed onto the tapering battery terminal 17. It is found more convenient to bend the wrench 9 as shown in Fig. 2. Of course in emergencies or other contingencies the wrenches 2 and 9 are more or less interchangeable and I do not limit 80 myself to the specific use that is made of them, but I do claim the combination of these elements with the terminal removing jaws and the relation of the latter to each and to the former.

95 The tongs are quite powerful and easily manipulated because the handles stand at right angles to the jaws. This makes it possible to use the tongs not only on battery terminals which stand vertically but as well 100 on those which are assembled horizontally.

It has been demonstrated after prolonged use that the extreme points of the flattened jaw 6 on account of their small area are bent down to such an extent as to make it 105 difficult to enter the jaw 6 between the shoulder of the battery post, not shown, and the terminal 18, in which case the elimination of concave end 7 is found to be an advantage. This elimination leaves the front of 110

the jaw 6 straight in the shape of a sharp chisel edge which will always enter any narrow spaces found between the battery post shoulder and the terminal 18.

5. What I claim is

1. In battery terminal tongs, a pair of handles pivoted to each other, a flat chisel shaped extension to one of the handles projecting approximately at right angles to the handle in two directions, an upwardly projecting reverse curved extension to the other handle, and a conical termination at the end of the curved extension.
- 10 2. In battery terminal tongs, suitable handles pivoted together near one end, an offset jaw projecting from one handle approximately at right angles in two directions, an upwardly projecting reverse curve extension from the other handle projecting approximately in line with the center of the lower jaw, a sharp pointed end at the terminus of such extension, and means for pivoting the handles to each other.

3. In battery terminal tongs, suitable handles having enlarged flattened bearing surfaces near one end, a pivot pin for holding these surfaces in engagement with each other, a transverse and sidewise projection from the one handle below the pivot, and an upwardly extending reversed curve projection of the other handle terminating above the pivot center.

4. In battery terminal tongs, suitable handles having enlarged bearing surfaces near one end and their other end terminating in adjacently positioned serrations, pivotal means for holding the flattened bearing surfaces in engagement with each other, a transverse and sidewise projection from the one handle below the pivot, and an upwardly extending reversed curve projection of the other handle terminating above the pivot center.

In testimony whereof I affix my signature.

ALBERT L. ZIMMERMAN.
